UNITED STATES PATENT OFFICE.

DAVID W. LLOYD, OF PITTSBURG, PENNSYLVANIA.

MOLDING-MACHINE.

SPECIFICATION forming part of Letters Patent No. 787,198, dated April 11, 1905.

Application filed July 23, 1904. Serial No. 217,814.

To all whom it may concern:

Be it known that I, DAVID W. LLOYD, a citizen of the United States, residing at Pittsburgh, in the county of Allegheny and State of Pennsylvania, have invented certain new and useful Improvements in Molding-Machines, of which the following is a specification, reference being had therein to the accompanying drawings, forming part of this specification, in which—

Figure 1 is a side elevation of my improved molding-machine. Fig. 2 is a plan view. Fig. 3 is an end view. Fig. 4 is a cross-section on the line IV IV of Fig. 1, showing the sides extended to their limit in dotted lines. Fig. 5 is a longitudinal sectional view of the machine indicated by the line V V of Fig. 2. Fig. 6 is a similar view showing the end gates tilted outwardly. Fig. 7 is a detail sectional view showing the adjusting-screw, bushings, housings, and sides assembled, indicated by the line VII VII of Fig. 2. Fig. 8 is a detail view of one of the housings. Fig. 9 is a detail view showing the shield for protecting the screw.

My invention consists of an improvement in machines for molding building-blocks or any similar articles of concrete, cement, or other plastic material.

The objects in view have been to provide a machine of simple construction and ready and easy adjustment adapted to a wide range of sizes, and particularly adapted to the manufacture of an absolutely accurate uniform block.

Referring now to the drawings, 2 represents the supporting-framework of the machine, made in any convenient manner of suitable material, as angle or other structural form, and provided with longitudinal platform-bars 3, one at each side, having notches or recesses 4, adapted to receive and support cross-bars 5 for the bottom-board, and also the end-gates 6, one at each end. These gates are preferably of cast-iron and provided at their bottoms, inside of their center of gravity toward the interior of the machine, with trunnion-bars 7, also seated in recesses 4. Several such recesses are provided in the platform-bars at their ends and at each side, allowing

for the location of the bars 5 and trunnion 7 at varying positions endwise, according to the length of block desired.

8 8 are the sides of the machine, also preferably of cast-iron, arranged vertically at each side and adapted to be moved inwardly and outwardly toward each other simultaneously by means of threaded shafts 9 at each end of the machine. The threads of each shaft at each end are right and left, respectively, and engage bushings 10 in housings 11, mounted in each end of the sides 8, as clearly shown, the sides embracing the housings, which in turn bear by a lip 12 upon the end bars 13 of the machine, thus relieving the weight from the threaded shafts.

The housings 11, as shown, are provided with top, bottom, and inner end grooves arranged to receive the corresponding surrounding terminal bearing portions of the sides. The bushings 10 are inserted and secured to the housings, which by their flanges at each side of the grooves engage and transmit the moving power of the screws to the sides. By this construction the entire screw, bushings, and housings may be moved endwise from the sides and as readily inserted without taking apart.

The sides are provided with diagonally-located cam projections 14 and oppositely-located bearing-lugs 15, respectively, by which the end gates are forced inwardly and maintained vertically, as in Fig. 5, against end thrust during filling and packing of the machine.

The shafts 9 are geared together by sprocket-wheels 16 16 and a connecting-chain at one side, one of the wheels or the shaft being provided with a crank-handle 17, by which means simultaneous movement is imparted to the shafts in one direction or the other to open or close, as will be readily understood.

A base-board 18 of a length to fit between the end gates when erect and of a width corresponding to the desired width of the block 95 rests upon the cross-bars 5, as shown. When the sides are separated, as in Fig. 4, the end gates fall outwardly by gravity against shafts 9, allowing the base-board and the molded block to be removed and a new board inserted.

Upon reversing the shafts the sides are drawn together until brought into contact with the base-board, the cams 14 meanwhile bearing against the diagonal sides of the end gates and 5 forcing them inwardly to a vertical position, the gates also then being clamped between the sides and also resting outwardly against the bases of the cams and the abutments 15, as already described. It will be seen that by the 10 location of the trunnions 7 the gates will always bear outwardly toward the cams, and these, as well as the abutments 15, are preferably adjustably secured to the sides, so that they may be set inwardly to correspond with 15 inward location of the gates in trunnion-bearings 4.

For the purpose of protecting the screws 9 from the material being used shields 19 are secured upon the outer sides of the end gates, 20 preferably arranged in the arc of a circle from the center of the trunnion-bearings, as shown, thus completely covering them at all positions of the gates.

When desired, several blocks of reduced 25 size may be made at one time by inserting cross-partitions 20 (indicated in dotted lines in Fig. 5) of the full height of the sides, or two or more blocks of narrower width may be made by inserting longitudinal partitions 30 21 between the end gates in the same manner, said cross or longitudinal partitions resting on the base-board. It will be observed that the lateral adjustment of the sides may be made within a comparatively wide range, as 35 indicated in dotted lines in Fig. 4, and a special advantage of such construction is that I am thereby enabled to use the machine to advantage in making a double block provided with a breaking-groove centrally along its bottom, 40 ends, and top. This adaptation of the machine is indicated in dotted lines by the groove-forming edges or partitions 22, consisting of strips inserted between the end gates at the bottom and top and also vertically against the gates 45 in alignment with such partitions, by which means such a longitudinal surrounding groove is formed in the block during the molding operation. These partitions may be merely inserted at the desired positions to subdivide 50 the block into two or more sections, or they may be made permanent in the base-board and end gates, the gates being provided with receiving-slots for the top partition, and this adaptation of the machine will be readily understood without any further explanation. 55 An especial advantage of forming blocks in this manner is that after being partially dried the blocks may be split open by a chisel inserted in the groove. The block will break 60 apart with a natural fracture, the outer terminal edges of which will coincide throughout with the top, bottom, and end grooves, thereby retaining the general dimensions of the block as determined by the grooves, and 65 the intervening separated portion will have

the appearance of a natural break, thus giving a more realistic and desirable finish than can be secured by a rough-face mold and with a consequently varying surface.

The operation of the machine will be readily understood from the foregoing description. It is very simple, strong, accurate, composed of few parts, and is readily taken apart or adjusted to use in the manner described. It may be utilized, changed, or varied by the skilled mechanic in various details or features of construction; but all such changes or variations are to be considered as within the scope of the following claims.

What I claim is —

1. A molding-machine provided with permanently-upright laterally-adjustable sides, inwardly-adjustable tilting ends in operative engagement therewith, and means for adjusting the sides simultaneously, substantially as 85 set forth.

2. A molding-machine comprising a supporting-base, tilting ends, and permanently-upright laterally-adjustable sides adapted to operatively engage said tilting ends and to 90 clamp the ends and base, substantially as set forth.

3. A molding-machine provided with longitudinal bearing-bars having journal-bearing-receiving recesses, cross base-bars set therein, 95 tilting end gates also mounted in said recesses, and laterally-adjustable sides, substantially as set forth.

4. A molding-machine provided with longitudinal bearing-bars having receiving-recesses, cross base-bars set therein, tilting end gates also mounted in said recesses, and laterally-adjustable sides provided with cams for actuating the end gates, substantially as set forth.

5. A molding-machine provided with longitudinal bearing-bars having receiving-recesses, cross base-bars set therein, tilting end gates also mounted in said recesses, and laterally-adjustable sides provided with cams and 110 abutments for actuating and supporting the end gates, substantially as set forth.

6. A molding-machine provided with longitudinal bearing-bars having receiving-recesses, cross base-bars set therein, tilting end 115 gates also mounted in said recesses, and laterally-adjustable sides, provided with threaded bearings, with oppositely-threaded adjusting-screws in engagement therewith, substantially as set forth.

7. A molding-machine provided with longitudinal bearing-bars having receiving-recesses, cross base-bars set therein, tilting end gates also mounted in said recesses, and laterally-adjustable sides provided with threaded 125 bearings, with oppositely-threaded adjusting-screws in engagement therewith, and means for actuating the screws simultaneously, substantially as set forth.

8. In a molding-machine, the combination 130

of a supporting-framework provided with trunnion-bearings, a removable base-board, tilting end gates mounted in the bearings, and laterally-adjustable sides provided with means 5 for engaging and adjusting the end gates, substantially as set forth.

9. A molding-machine having permanently-upright sides and provided with outwardly-tilting end gates mounted on bearing-trunnions located at one side of their center of gravity, substantially as set forth.

10. A molding-machine provided with outwardly-tilting end gates mounted on bearing-trunnions located at one side of their center of 5 gravity and laterally-adjustable sides provided with means for forcing the end gates inwardly, substantially as set forth.

11. In a molding-machine the combination of a supporting-framework provided with trunnion-bearings, a removable base-board, tilting end gates mounted in the bearings, and laterally-adjustable sides provided with cams 5 adapted to engage the end gates to force them inwardly, substantially as set forth.

5 12. The combination of a supporting-frame,

a removable base-board, tilting end gates, laterally-adjustable sides provided with cams engaging the end gates, and right and left hand adjusting-screws engaging threaded portions of the sides, with means for actuating the 30 screws, substantially as set forth.

13. The combination with the adjusting-screws for the sides, of tilting end gates actuated by the sides provided with shields extending over the screws, substantially as set 35 forth.

14. In a molding-machine, the combination with the base-board, oppositely-adjustable tilting ends, and permanently-upright laterally-adjustable sides; of groove-forming 40 partitions clamped between the oppositely-adjustable ends or sides, extending across the mold area and adapted to form grooves in the block, substantially as set forth.

In testimony whereof I affix my signature in 45 presence of two witnesses.

DAVID W. LLOYD.
